UNITED STATES PATENT OFFICE.

EUGENE A. KEMPER, OF PHILADELPHIA, PENNSYLVANIA.

DESIGN FOR FRINGE.

SPECIFICATION forming part of Design No. 12,889, dated April 18, 1882.

Application filed February 7, 1882. Term of patent 3½ years.

To all whom it may concern:

Be it known that I, EUGENE A. KEMPER, a citizen of the United States, residing at Philadelphia, in the county of Philadelphia, 5 and State of Pennsylvania, have invented and produced a new and original Design for Fringe, of which the following is a specification, reference being had to the accompanying drawings, forming part thereof.

10 Of the drawings, Figure 1 represents in front elevation a fringe which illustrates my design. Fig. 2 represents in similar view, but in magnified detail, a portion of the same, designed to exhibit as well as is possible in black and 15 white drawing the employment of shaded tints in the crimped threads.

The fringe represented consists of a heading, A, attached to and depending from the lower edge of which is a continuous series of straight 20 threads, B. Both heading and threads are made of any fit material.

25 C are a series of loops or festoons, secured by rosettes or suitable attachments, D, to the heading so as to depend therefrom; and E are a series of bunches or tassels, so to speak, secured to the heading between the loops and depending therefrom in front of the straight threads. Both the loops and the bunches are made of crimped threads of suitable material,

so as to produce a novel and beautiful design 30 and effect heretofore unknown to fringe-manufacturers. I prefer to make both the loops and the bunches of crimped threads of shaded colors; but I do not restrict myself in this regard.

35 In the drawings the effect of different shades or colors of crimped threads when employed is represented in Fig. 2, somewhat imperfectly, however, as must necessarily be the case in black and white drawing.

40 The gist of the invention resides in the employment of crimped threads in connection with the straight threads and heading of ordinary fringes.

45 The precise arrangement of loops and bunches shown in the drawings may be modified or altered without departing from the invention.

I claim—

50 The design for a fringe herein shown and described, the same consisting of crimped threads, combined with the straight threads and heading of a common fringe.

In testimony whereof I have hereunto signed my name this 3d day of February, A. D. 1882.

EUGENE A. KEMPER.

In presence of—

W. C. STRAWBRIDGE,
J. BONSALL TAYLOR.
